UNITED STATES PATENT OFFICE

ALFRED G. LEGGE, OF BROCKTON, MASSACHUSETTS

SHOE FORM

Application filed November 1, 1929. Serial No. 404,052.

This invention relates to shoe forms for insertion in shoes to maintain their shape.

Such forms are commonly shaped over a last conforming substantially to the last upon which the shoe is lasted but being generally smaller an amount equal to the thickness of the material from which the shoe form is made. As a result, these forms are suitable only for use with shoes of the particular shape for which they were made, and if used in shoes of other shapes or sizes will not fit snugly against the soles of the shoes.

It is an object of the present invention to provide a shoe form which is capable of a more universal application by being adapted for use with a relatively large variety of shapes of shoes.

The present invention contemplates the provision of a shoe form shaped from a flexible sheet material, such as sheet celluloid, which is capable of being distorted to conform to the shape of the interior of the shoe in which it is used and at the same time fill out the shoe in a satisfactory manner. Celluloid forms as heretofore constructed have been subject to the same objectionable features as other forms, inasmuch as particular care has been exercised to make the form as rigid as possible. Such forms have been stiffened by an inturned flange extending around the entire bottom edge of the form. In accordance with the invention, while it is desirable to reinforce the form to a certain degree, the reinforcement is arranged so as to offer greater resistance to lateral movement, particularly the rear portion of the form than movement in other directions of the opposite side portions of the form. Consequently, when the form is inserted in shoes of varying shapes or styles the side portions of the form adjust themselves so as to conform to the sole and instep and at the same time fill out the shoe upper. Preferably, the form is reinforced by a flexible pivotally mounted cross member near the rear of the form thereby offering greater resistance to narrowing of the form at its rear than at its forward portion.

Before explaining in detail the present invention, it is to be understood that the in-

vention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the claim hereto appended as considered in view of the prior art and the requirements thereof.

The invention will be more clearly understood from the following description in conjunction with the accompanying drawings: in which,

Figs. 1 and 2 are top and bottom views of a shoe form embodying the invention;

Fig. 3 is a plan view of the form distorted by narrowing the forward portion of the toe part to conform to a particular style of shoe, the normal shape of the form being indicated in dotted lines;

Fig. 4 is a plan view of the form distorted by movement of one side of the form relative to the other side to conform to another style of shoe, the normal shape of the form being indicated in dotted lines; and

Fig. 5 is a sectional view taken upon the line 5—5 of Fig. 1.

A shoe form illustrating one embodiment of the invention is shown in the accompanying drawings and comprises a sheet of flexible material, such as sheet celluloid, shaped over a suitable last to provide a form 10 conforming substantially to the shape of the interior of a shoe upper. The bottom side edges of the form 10 are provided with inturned flanges 11 and 12 extending from the rear thereof forwardly and terminating respectively at points *a* and *b*. In the manufacture of forms of this general type it is common practice to stretch a suitably softened sheet of celluloid over the toe of a last so as to form an inturned flange around the entire bottom edge of the form. In producing the form embodying the invention the portion of the inturned flange at the forward or toe tip of the form is cut away between the points *a* and *b*.

and *b*, thereby lessening the tendency of the flange to reinforce the toe portion or forward end of the form. The celluloid is shaped over the instep portion of the last so that the top or upper portion of the form connects the rear ends of the flanges 11 and 12 providing portions *c* and *d* adapted to engage the instep of the shoe when the form is placed therein. The form is further reinforced by a flexible cross member, such as a wire 15, extending between and connected, as by rivets 16, to the rear portions of the in-turned flanges 11 and 12. Preferably, the flexible reinforcing member is pivotally connected to opposite sides of the form. For this purpose the ends of the wire 15 are looped around the rivets 16 so as to form a pivotal connection therewith.

By way of illustration some of the advantages of the form of the invention are illustrated in Figs. 3 and 4. It will be noted in Fig. 3 that the forward end of the form 10 is distorted a considerably greater extent than the rear portion of the form thereby rendering the form suitable for use in a shoe having a pointed toe. In Fig. 4 the form 10 is shown with the opposite side portions adjusted relatively so as to bring the portions *c* and *d* into engagement with the edge of the instep of a shoe of different style, the normal relative positions of the parts of the form, particularly the portions *c* and *d* being indicated in dotted lines. It will be apparent, therefore, that the shoe form of the invention is reinforced so as to offer less resistance to distortion at the forward portion than at the rear portion of the form as well as a greater resistance to relative lateral movement of opposite sides, particularly the rear portions thereof, than to relative longitudinal movement. Thus, when the form of the invention is inserted in a shoe it automatically adjusts itself so as to bring the portions *c* and *d* in engagement with the instep of the shoe and to fill out the shoe upper in a satisfactory manner. It will be apparent, therefore, that by reducing the reinforcement for the forward portion of the form in accordance with the invention, the form has a universal application by being adapted to conform to shoes of different shape, whereas forms of this general type as constructed heretofore were adapted for use only in the particular style for which they were made.

I claim:

In a shoe form, a toe part composed of flexible sheet celluloid which is reinforced by an in-turned flange on the bottom of each side portion thereof only, each of said in-turned flanges extending substantially the entire length of said side portions, and a member pivotally connected at its ends to said flanges, the flexibility of the toe tip portion of the form being such that it may be distorted to

move one side of said form substantially bodily longitudinally and laterally relative to the other side of the form.

In testimony whereof I affix my signature.

ALFRED G. LEGGE.
